CLAIM

The ornamental design for a network tap, as shown and described.

DESCRIPTION

FIG. 1 is a first perspective view of a network tap showing the new design, which shows a front of the network tap; FIG. 2 is a second perspective view thereof, which shows a back of the network tap;

FIG. 3 is a right side elevational view thereof;

FIG. 4 is a left side elevational view thereof;

FIG. 5 is a front elevational view thereof;

FIG. 6 is a back elevational view thereof;

FIG. 7 is top plan view thereof; and,

FIG. 8 is a bottom plan view thereof.
